HAIR WAVING HEATER

Ernest O. Frederics, New York, N. Y., assignor
to E. Frederics, Inc., New York, N. Y., a Cor-
poration of New York

Application February 15, 1929
Serial No. 340,095

22 Claims. (Cl. 219—24)

This invention relates to heaters for use in hair waving operations, and, more particularly, to heater units which may be clamped about tresses of hair wound upon a curler.

5 In general, it is an object of the invention to provide a device of the character described which will efficiently perform the purpose for which it is intended, which is simple and economical of construction, which can be expeditiously, conveniently and safely manipulated, and which can be readily manufactured and assembled.

More particularly, it is an object of the invention to provide a heater which may be clamped 15 upon a winding of hair in a single easy operation.

Another object is to provide in a heater adapted to be employed in hair-waving operations improved heat-insulating means for protecting the 20 hands of an operator.

A more specific object is to provide improved means for insulating the hand of an operator from a clamp-manipulating arm.

Another object is to provide means for equalizing the spreading and clamping movements of 25 elements by which the winding of hair is clamped.

Still another object is to provide a device which is so constructed that the danger of the 30 same slipping from the hands of an operator is minimized.

A still further object is to provide a mechanically strong but light-weight heater, the use of which assures a maximum of safety and comfort on the part of the person being treated.

Other objects of the invention will in part be obvious and will in part appear hereinafter.

The invention accordingly comprises an article of manufacture possessing the features, 40 properties, and the relation of elements which will be exemplified in the article hereinafter described, and the scope of the application of which will be indicated in the claims.

For a fuller understanding of the nature and 45 objects of the invention reference should be had to the following detailed description taken in connection with the accompanying drawings, in which:

Figure 1 is a perspective view of one form of 50 heater embodying the invention;

Fig. 2 is a section taken in the direction of the arrows along the line 2—2 in Fig. 1;

Fig. 3 is an end view of the heater, showing the same in open position;

55 Fig. 4 is a front view thereof;

Fig. 5 is a side view illustrating the heater in operative position upon a coil of hair wound on a curler, certain of the members being partly broken away;

Fig. 6 is a perspective view of a modified form 60 of heater embodying the invention;

Fig. 7 is a section taken in the direction of the arrows along the lines 7—7 of Fig. 6;

Fig. 8 is an end view of the modified form of heater showing the same in open position; and 65

Fig. 9 is a side view of the modified form of heater.

In hair waving operations, because of the number of windings of hair treated simultaneously, and the annoyance to which the subject 70 is exposed by delays in putting in place the hair waving devices upon her head, it is of extreme importance to provide devices which may be manipulated with extreme ease and with a minimum of delay. It is also important not only for 75 the operator to be able to easily and expeditiously handle the devices, but also that he should be fully protected from the heat employed in the operations. Moreover, on account of the large number of devices used in such operations, 80 and of the number of times they are used, it is necessary that the devices be both economical of manufacture and simple and sturdy in construction.

There are exemplified two forms of heaters 85 which satisfy in a marked degree the various needs of a heating unit for hair waving operations. In their exemplified form, the heaters are particularly adapted for use in the "Cro- 90 quignole" method of waving, wherein the tresses of hair are wound upon themselves on a curler; but many of the features of the device are capable of being embodied in various other types of hair waving heaters.

The form of heater exemplified in Figs. 1 to 95 5 comprises a heating element 10 wound about a strip 11 of insulating material, such as mica, and surrounded by a layer 12 of insulating material, such as mica; the whole being contained in a crescent-shaped casing 13. The casing comprises a curved face plate 14 and a back plate 15, the former being in the shape of a trough 100 to fit about a winding of hair on a curler and the latter being shaped to hold the heating element firmly in place in the casing. The face plate 14 is bent over at its side edges to hold the back plate 15 in place, and in order to close the casing at its ends and to more securely retain the back plate, the ends of the face plate 14 are 105 split to provide a plurality of fingers 16 which 110

are bent over the ends of the plate 15. Mounted on the back of the plate 15 is a curved supporting plate 17 secured in place by pins 18, and suitable mounting means for the leads 19 which 5 conduct current to the heating element. This mounting means comprises an insulating block 20 fastened on the plate 15, and an insulating block 21 secured to the block 20 by screws 22. The edges of the plate 17 extend beyond the 10 sides of the casing and there is secured to each edge at 23 one of a pair of hingedly mounted arms 24 to each of which is secured, by means of screws 25, one of a pair of curved clamping elements 26 which are adapted to cooperate 15 with the plate 14 to grip a winding of hair. Suitable means, as a spring 27, are preferably provided to normally maintain the clamping elements in gripping position. In order to permit the safe and easy manipulation of the device 20 each of the arms carries an insulating block 28 which is secured to the plate by means of pins 29 and upon each of the blocks 29 there is secured by means of pins 30 a supplemental block 31 which is separated from the block 28 by suitable 25 means, such as the washers 32, to provide an air space 33 between the blocks 28 and 31. This air space serves to augment the insulating properties of the blocks themselves and to insure against the transmission of any substantial 30 amount of heat from the heating element to the fingers of the operator. In the exemplified apparatus there are provided gripping members 34 which are secured against the block 31 by means of one of the screws 30.

35 The exemplified device is particularly adapted for use, and in Fig. 5 is shown as used, in connection with a curler 36 which may be of the type exemplified in my copending application Ser. No. 311,994, filed October 12, 1928, which 40 curler is adapted to be supported in a supporting clamp 37, which may be of the type exemplified in my copending application Ser. No. 323,057, filed December 1, 1928.

45 In practice the gripping members 34 are gripped between the thumb and forefinger of an operator and pressed together so as to spread the clamping elements 26, and the unit is then moved over a winding of hair 35 on a curler, such, for example, as shown at 36, a pad or sheet 50 38 of suitable material being ordinarily interposed between the hair and surfaces of the members 14 and 26. After the waving operation is completed the device is then readily removed by again pressing the gripping members 34 toward each other; it being noted that the insulating blocks and the air space therebetween serve to prevent the gripping members from being heated, regardless of the duration of the heating.

60 The form of heater exemplified in Figs. 6 to 9, inclusive, comprises a heating element 40 wound about a strip 41 of mica or other insulating material and surrounded by a layer 42 of similar insulating material, the whole being enclosed in 65 a casing 43. The casing comprises a curved or trough-like face plate 44 and a back plate 45, the sides and ends of the former being bent upwardly about the side of the end edges of the latter. Lugs 46, extending over the ends of the 70 outer surface of the back plate, serve to hold the parts of the casing securely together. Mounted on the outer surface of the back plate is a supporting plate 47 secured in place by pins 48, and suitable mounting means for the leads 49 which conduct current to the heating ele-

ment. This mounting means comprises a pair of blocks 50 and 51 held together by screws 52 and adapted to fit over one or the other of the conductors 49. To each edge of the supporting plate 47 there is pivotally secured at 53 one of a pair of arms 54, each of which carries a curved clamping element 56. The clamping elements 56 cooperate with the curved plate 44 to grip a winding of hair.

80 In the form here exemplified a single means is provided for operating the two arms 54. Pivotally secured to each side of each carrier element at 57 is a link 58, each set of links being pivotally connected to each other by a pin 59 carried on a transverse brace 60. This brace carries a 85 sleeve 61, which is slidably mounted on a rod 62 extending outwardly from the back of the casing. At the end of the rod 62 is an insulating cap 63, and between the cap and the sleeve 61 is a coil-spring 64 which tends to maintain the 90 sleeve in a depressed position and to maintain the clamping elements 56 in a position adjacent the concave surface of the plate 44. In order to withdraw the sleeve and to spread the clamping elements, there is secured to the sleeve by 95 suitable means, as by a pin 65, or by being molded thereon, a manipulating element 66, which is constructed of insulating material, as is the cap 63, to protect the hands of an operator from the heat generated by the heating element. The forward side of the element 66 is 100 preferably cut away somewhat, as indicated at 67, to permit the same to be more easily gripped. In order to protect the hands of the operator more effectively from the heat of the metallic 105 parts of the unit and from steam or other hot gases evolved during the hair-waving process, there is provided between the element 66 and the brace 60 a baffle plate 68 of heat-insulated material, which, as exemplified, is mounted against 110 a washer 69.

115 In practice, the operator places his palm over the cap 63 and, grasping the element 66, draws the same, together with the sleeve 61, rearwardly along the rod 62 against the pressure of the 120 spring 64, with the result that the brace 60 is drawn rearwardly so as to swing the arms 54, together with the clamps 66, outwardly. The unit is then moved over a winding of hair and the element 66 released, whereupon the spring 125 64 will operate to move the clamping elements 56 against the winding. By this arrangement the chance of the heater unit slipping from the hands of the operator is minimized, and the spreading and clamping movements of the 130 clamping elements is positively equalized, so that certainty of operation is combined with ease of manipulation.

135 The exemplified devices can be put in place and removed with the utmost ease so that annoying delays in the hair-waving process are avoided. They are sturdy and substantial, and at the same time economical of construction, and satisfactorily perform all the uses to which a heater of this type is put.

140 Since certain changes may be made in the above article, and different embodiments of the invention could be made, without departing from the scope thereof, it is intended that all matter contained in the above description or shown in the accompanying drawings shall be interpreted 145 as illustrative and not in a limiting sense.

150 It is also to be understood that the following claims are intended to cover all of the generic and specific features of the invention herein

described, and all statements of the scope of the invention which as a matter of language might be said to fall therebetween.

Having described my invention, what I claim as new and desire to secure by Letters Patent is:

5. 1. In a heater for use in hair waving operations, the combination of a heating element, means for mounting the heating element, a supporting plate secured to said mounting means, a pair of clamps hingedly connected to the supporting plate, means for manipulating each of said clamps, and resilient means tending to move each of said clamps toward said heating element, whereby said clamps may be manipulated to fit about a winding of hair and when in operative position to clamp said heating element in position adjacent the winding of hair. 80
10. 2. In a heater for use in hair waving operations, the combination of a heating element, a supporting plate, means to mount the heating element on the supporting plate, a pair of arms hingedly connected to opposite edges of the supporting plate, a clamp carried by each arm, said clamps being adapted to cooperate to clamp said mounting in position to hold said heating element adjacent a winding of hair, and means connected with said arms for manipulating said clamps, said means including an insulating block. 85
15. 3. In a heater for use in hair waving operations, the combination of a heating element, a supporting plate, means to mount the heating element on the supporting plate, a pair of arms hingedly connected to opposite edges of the supporting plate, a clamp carried by each arm, said clamps being adapted to cooperate to clamp said mounting in position to hold said heating element adjacent a winding of hair, and means on each of said arms for manipulating said clamps, each of said means including a pair of spaced insulating blocks. 90
20. 4. In a heater for use in hair waving operations, the combination of a heating element, a curved casing therefor, a supporting plate having a greater radius than the curve of said casing and secured in tangential relation thereto, a pair of clamping elements hingedly mounted on each edge of the supporting plate, and means for manipulating said clamping elements to permit the same to be moved about a winding of hair. 95
25. 5. In a heater for use in hair waving operations, the combination of a heating element, a crescent shaped container therefor, a supporting plate mounted on the convex side of said container, a portion of said plate being adjacent an edge of said container, a clamping element mounted on said portion for movement toward the concave side of the container, and means to move said clamping element toward said concave side to press the latter toward a winding of hair. 100
30. 6. In a heater for use in hair waving operations, the combination of a heating element, a container therefor, supporting means on said container, a pair of arms, each pivotally mounted by said supporting means, means for manipulating said arms, and means for protecting the ends of a conductor leading to said heating element, said means comprising an insulating block mounted on said container, and a second insulating block removably secured to the aforesaid block, said blocks being adapted to fit over said conductor. 105
35. 7. In a heater for use in hair waving operations, the combination of a trough-like face plate, a heating element mounted on the convex side of said plate, a supporting plate beyond said heating element, means to secure the supporting plate to the face plate, a pair of clamping elements hingedly connected with the supporting plate and adapted to cooperate with said face plate to grip a mass of hair wound on a curler, and an operating arm for each of said clamping elements. 110
40. 8. In a heater for use in hair waving operations, the combination of a trough-like face plate, a heating element mounted on the convex side of said plate, a supporting plate beyond said heating element, means to secure the supporting plate to the face plate, a pair of clamping elements hingedly connected with the supporting plate and adapted to cooperate with said face plate to grip a mass of hair wound on a curler, an operating arm for each of said clamping elements, an insulating block on each arm, and a supplemental insulating block on each arm spaced from the aforesaid block, whereby the clamping elements may be readily manipulated by an operator. 115
45. 9. In a heater for use in hair waving operations, the combination of a curved face plate, a heating element disposed against the convex surface of the plate, a curved back plate disposed over the heating element, the side edges of said face plate being bent about the edges of said back plate and the end edges of said face plate being each divided in a plurality of fingers each of which is bent over the end edge of said back plate, and means connected with the back plate for clamping the face plate about a winding of hair. 120
50. 10. In a heater for use in hair waving operations, the combination of a heating element, a container therefor, supporting means on said container, a pair of arms, each pivotally mounted by said supporting means, a clamping element on each of said arms, means for manipulating said arms, a reciprocable element, and means for connecting each of said arms with said reciprocable element whereby said clamping elements may be moved in response to the reciprocation of the reciprocable element to grip a mass of hair wound on a curler. 125
55. 11. In a heater for use in hair waving operations, the combination of a heating element, a container therefor, supporting means on said container, a pair of arms, each pivotally mounted by said supporting means, means for manipulating said arms, a link pivotally connected to each arm, an element projecting from said container, a plunger slidably mounted on said projecting element, means for pivotally connecting said plunger and said arms, and insulating members secured respectively to said projecting element and to said plunger for manipulating the plunger. 130
60. 12. In a heater for use in hair waving operations, the combination of a heating element, a container therefor, supporting means on said container, a pair of arms, each pivotally mounted by said supporting means, means for manipulating said arms, a link pivotally connected to each arm, an element projecting from said container, a plunger slidably mounted on said projecting element, means for pivotally connecting said plunger and said arms, and a baffle plate composed of insulating material and mounted between said container and said manipulating members. 135
65. 13. In a heater for use in hair waving operations, the combination of a heating element, a container therefor, supporting means on said container, a pair of arms, each pivotally mounted by said supporting means, means for manipulating said arms, a link pivotally connected to each arm, an element projecting from said container, a plunger slidably mounted on said projecting element, means for pivotally connecting said plunger and said arms, and a baffle plate composed of insulating material and mounted between said container and said manipulating members. 140
70. 14. In a heater for use in hair waving operations, the combination of a heating element, a container therefor, supporting means on said container, a pair of arms, each pivotally mounted by said supporting means, means for manipulating said arms, a link pivotally connected to each arm, an element projecting from said container, a plunger slidably mounted on said projecting element, means for pivotally connecting said plunger and said arms, and a baffle plate composed of insulating material and mounted between said container and said manipulating members. 145
75. 15. In a heater for use in hair waving operations, the combination of a trough-like face plate, a heating element mounted on the convex side of said plate, a supporting plate beyond said heating element, means to secure the supporting plate to the face plate, a pair of clamping elements hingedly connected with the supporting plate and adapted to cooperate with said face plate to grip a mass of hair wound on a curler, an operating arm for each of said clamping elements, an insulating block on each arm, and a supplemental insulating block on each arm spaced from the aforesaid block, whereby the clamping elements may be readily manipulated by an operator. 150

tions, the combination of a heating element, a container therefor, supporting means on said container, a pair of arms, each pivotally mounted by said supporting means, means for manipulating said arms, a rod projecting from the rear of said container, a sleeve slidably mounted on the rod, a link pivotally connected to each arm, said links being pivotally connected to each other and to said sleeve, an insulating cap on the end of said rod, and an insulating manipulating member on said sleeve.

14. In a heater for use in hair waving operations, the combination of a heating element, a container therefor, supporting means on said container, a pair of arms, each pivotally mounted by said supporting means, means for manipulating said arms, a rod projecting from the rear of said container, a sleeve slidably mounted on the rod, a link pivotally connected to each arm, said links being pivotally connected to each other and to said sleeve, an insulating cap on the end of said rod, and a spring inserted between said cap and said sleeve.

15. In a heater for use in hair waving operations, the combination of a heating element, a container therefor, supporting means on said container, a pair of arms, each pivotally mounted by said supporting means, means for manipulating said arms, a rod projecting from the rear of said container, a sleeve slidably mounted on the rod, a link pivotally connected to each arm, said links being pivotally connected to each other and to said sleeve, an insulating cap on the end of said rod, and a baffle plate mounted on said sleeve at a point between said manipulating member and said heating element.

16. In a heater for use in hair waving operations, the combination of a heating element, a metallic mounting therefor, means for clamping a winding of hair against said mounting, an element composed of insulating material and operable from the side nearest said mounting for manipulating said clamping means, and a baffle member composed of insulating material and disposed between said manipulating element and said mounting means.

17. In a heater for use in hair waving operations, the combination of a heating element, a crescent-shaped container therefor, a supporting plate mounted on the convex side of said container, a clamping element independently mounted on each side of said supporting plate for movement toward the concave side of the container, and means to move said clamping elements toward said concave side to press the latter toward a winding of hair.

60

135

65

140

70

145

75

150

18. In a heater for use in hair waving operations, the combination of a plate arcuate in cross section and adapted to receive a winding of hair, a heating element disposed adjacent the convex side of said plate, supporting means fixedly mounted with respect to said plate, a pair of arms hingedly carried by said supporting means, an arcuate clamping element carried by each of said arms, said arcuate clamping elements having defined gripping edges and being movable toward said arcuate plate to form a continuous arcuate surface therewith and to embrace a winding of hair, and means to manipulate said arms.

19. In a heater for use in hair-waving operations, the combination of a heating element, a container therefor, supporting means on said container, means for clamping a winding of hair against said supporting means, said clamping means being pivotally mounted on said supporting means and toggle joint means for manipulating said clamping means.

20. In a heater for use in hair-waving operations, the combination of a heating element, a metallic support therefor, a metallic arm pivotally mounted on said support, a clamping element at one end of said arm, and a handle at the other end of said arm, said handle comprising a piece of heat-insulating material spaced from said arm throughout substantially its entire extent, and a second piece of heat-insulating material spaced from the first piece of insulating material throughout substantially its entire extent.

21. In a heater for use in hair waving operations, the combination of a trough-like face plate, a heating element on the convex side of the plate, a pair of pivot pins symmetrically disposed on either side of a longitudinal plane bisecting said plate, a clamping element pivotally supported from each pin, and an operating handle therefor above said pin, said clamping elements being adapted to press against said plate a mass of hair wound on a curler.

22. In a heater for use in hair waving operations, the combination of a trough-like face plate, a heating element mounted on the convex side of said plate, supporting means mounted beyond said heating element and spaced from each other to permit free circulation of air thereabout, and a pair of clamping elements hingedly mounted on said supporting means and movable toward each other and transversely of said face plate to cooperate with said face plate and to grip a mass of hair wound on a curler.

ERNEST O. FREDERICKS.
